UNITED STATES PATENT OFFICE.

JOSEPH I. COMBER, OF PHILADELPHIA, PENNSYLVANIA.

DESIGN FOR A CIGAR-SIGN.

SPECIFICATION forming part of Design No. 37,333, dated February 14, 1905.

Application filed August 14, 1903. Serial No. 169,554. Term of patent 7 years.

To all whom it may concern:

Be it known that I, JOSEPH I. COMBER, a citizen of the United States, residing at Philadelphia, in the county of Philadelphia and State of Pennsylvania, have invented a new, original, and ornamental Design for a Cigar-Sign, of which the following is a specification, reference being had to the accompanying drawing, forming part thereof.

5 The drawing is a plan view of my new design for a cigar-sign.

What I claim as new, and desire to secure by Letters Patent, is—

The ornamental design for a cigar-sign as shown.

JOSEPH I. COMBER.
